UNITED STATES PATENT OFFICE

2,380,986

ELEVATING SCRAPER

George W. Mork, South Milwaukee, Wis., assignor
to Bucyrus-Erie Company, South Milwaukee,
Wis., a corporation of Delaware

Application February 12, 1944, Serial No. 522,041

8 Claims. (Cl. 37—133)

My invention relates to new and useful improvements in elevating scrapers.

The tractor-pulled earth-moving scraper is now well known in the art. Such scrapers have, for many purposes, replaced the combination of a power-shovel or drag-line excavator with a fleet of dump-trucks.

But, as the use of such scrapers has gradually been extended to longer and longer hauls, the inefficiency of using digging equipment to haul, and hauling equipment to dig, has become more and more evident. More tractive force is needed for digging than for hauling, and the use of this added tractive force is a waste during hauling, when the speed-factor of the power is made important. The characteristics of digging tractive power and hauling tractive force are thus seen to be quite different, and the improvement of the traction device with either of these two ends in view, renders it less efficient for the other purpose, thus necessitating a compromise. The purely digging parts of the scraper represent a very large portion of the total weight of the scraper, and it is obviously wasteful to have to lug this excess weight all the way from the dig to the dump and back.

The best that has been suggested in the past to meet this situation has been to use two traction elements, one pulling and the other pushing the scraper. The pulling element is primarily designed for running over roads; one of these is permanently attached to each scraper, sometimes even being built-in. The pushing element is primarily designed to supply tractive force during digging; one such element usually serving several scrapers.

But it will readily be seen, that this expedient only partially solves the above-recited problems.

Accordingly it is the principal object of my present invention to devise a scraper which can elevate to dump into a truck.

The advantages of digging by scraper can thus be retained. The scraper and its hauling tractor can be built with but one end in view, namely, efficient digging, rather than as a compromise between digging and carrying. And the carrying can be done by trucks especially designed for that purpose.

My invention is particularly adapted to rear-dumping scrapers of the generic sort shown and described in U. S. Patents Nos. 2,010,801 to W. J. Adams, Re. 21,170 to T. R. Paulsen, and 2,308,534 to T. R. Paulsen.

In addition to my principal objects, above stated, I have worked out a number of novel and

useful details, which will be readily evident as the description progresses.

My invention consists in the novel parts and in the combination and arrangement thereof, which are defined in the appended claims, and of which one embodiment is exemplified in the accompanying drawings, which are hereinafter particularly described and explained.

Throughout the description the same reference number is applied to the same member or to similar members.

Figure 1 is a plan view of my scraper in digging position.

Figure 2 is a side elevation of my scraper, in carrying position.

Figure 3 is a side elevation of the same scraper, in digging position.

Figure 4 is a front elevation of the same scraper.

Figure 5 is a side elevation of the same scraper, in elevated dumping position.

Referring to the figures, we see that the main frame of my scraper comprises two side-beams 11, a cross-beam 12, a draft tongue 13, four vertical beams 14, 15, and a top cross-beam 16.

The main frame is supported on two wheels 17, or other equivalent means.

An auxiliary frame, comprising two side-beams 18 and a cross-beam 19, is pivoted low down on the main frame on transverse horizontal pivots 20.

A second auxiliary frame, comprising two side-beams 21 and a cross-beam 22, is pivoted high up on the main frame on transverse horizontal pivots 23.

These two auxiliary frames together constitute a sort of converging pantograph linkage for simultaneously raising and tilting the bowl 24, which is pivotally supported by the lower auxiliary frame at 25, and to the higher auxiliary frame at 26.

The bowl has sides and a bottom, but is open at the top and at both ends. Along the front of the bottom, there is a digging-edge 27, preferably but not necessarily of the sort covered by U. S. Patent No. 2,257,761, to T. R. Paulsen.

The rear end of the bowl is closed by an end-gate 28, and the front end by an apron 29. The end-gate is supported on arms 30, and the apron is supported on arms 31, both sets of arms being pivoted to the sides of the bowl 24. As shown, both sets of arms are pivoted on one and the same axis 32. Neither the end-gate nor the apron need be pivoted in any particular way.

The lower auxiliary frame 18 supports two

rollers 33, on which rest the forward ends of the apron-arms 31.

The operations of my scraper are controlled by two ropes, which are actuated by a two-drum winch (not shown) mounted on and powered by the tractor (not shown) which drags my scraper.

Rope 34 extends from an anchorage 35 on the end-gate 28, thence over sheaves 36, 37, 38 and 39 on the upper auxiliary frame, and sheaves 40, 41 and 42 on the main frame, to the winch on the tractor. This rope serves to open and close the end-gate 28.

Rope 43 extends from an anchorage 44 on the lower auxiliary frame, thence over several sheaves 45 on the main frame and sheaves 46 on the auxiliary frame, thence over sheave 47 on the main frame across the frame and around sheave 48, thence over several sheaves 45 and 46 on that side of the scraper, thence back across the main frame via sheaves 49 and 50, thence around some more sheaves 45 and 46 on the original side of the scraper, and thence by sheaves 51, 52 and 53 to the winch on the tractor. This rope serves to raise and lower the bowl.

However, other means than ropes could be used.

The operation of my invention is as follows:

Starting from the carrying position of Figure 2, if rope 43 be paid out, the bowl will descend to the digging position of Figure 3. The front ends of apron-arms 31, bearing against rollers, will open apron 29, so as to permit the dirt, cut by digging-edge 27, to enter bowl 24. Other means for opening the apron could be used.

When the bowl has been filled, the pulling-in of rope 43 will raise the bowl 24 to the carrying position of Figure 2, and apron 29 will close on the load as there shown.

Further pulling-in of rope 43 will raise the bowl 24 to the position of Figure 5, but with the end-gate 28 still closed, rather than as shown.

Inasmuch as side-beams 16 of the main frame are spaced apart, and as the axles of wheels 17 do not extend across from wheel to wheel, a dump truck can back in under bowl 24. End-gate 28 can then be opened, by pulling on rope 34, so as to dump the contents of the bowl into the truck.

The camber in side-beams 16 of the auxiliary frame, should be noted. This camber serves two purposes. First, it permits these side-beams to clear side-beams 16 of the main frame in the digging position illustrated in Figure 3. Secondly, it prevents obstructing the backing-in of a dump truck when my scraper is in the dumping position of Figure 5.

Having now described and illustrated one form of my invention, I wish it to be understood that my invention is not to be limited to the specific form or arrangement of parts herein described and shown, except insofar as required by limitations in my claims.

I claim:

1. In an earth-moving scraper, the combination of: a ground support; an earth-holding bowl, having sides, a bottom, and an earth-cutting edge at the forward end of the bottom; two sets

of arms to support the bowl on the ground support, said sets being pivotally attached to the bowl on two respective vertically spaced horizontal axes, and to the ground support on two respective vertically more spaced horizontal axes, both of said sets of arms extending rearwardly from their pivots on the ground support to their pivots on the bowl whereby said bowl is supported by the ground support for tilting and bodily lifting and lowering; operating means to lift the bowl, from a forwardly inclined digging position, through a substantially level carrying position, to a rearwardly inclined very elevated dumping position; an end-gate to close the rear end of the bowl; an apron to close the front end of the bowl; separate operating means, to open the end-gate; and automatic means, to open the apron whenever the bowl is tilted to digging position, and to permit the apron to close in all other positions.

2. A scraper according to claim 1, further characterized by the fact that the ground support is forked rearwardly, so as to permit a truck to back in under the bowl when the latter is raised.

3. A scraper according to claim 1, further characterized by the fact that the lower set of arms is upwardly cambered.

4. A scraper according to claim 1, further characterized by the fact that the lower set of arms is upwardly cambered; and that the ground support is forked rearwardly, so as to permit a truck to back in under the bowl when the latter is raised.

5. In an earth-moving scraper, the combination of: a ground support; an earth-holding bowl having an earth-cutting edge at the forward end; two sets of arms to support the bowl on the ground support, said sets being pivotally attached to the bowl on two respective vertically spaced horizontal axes, and to the ground support on two respective vertically more spaced horizontal axes, both of said sets of arms extending rearwardly from their pivots on the ground support to their pivots on the bowl, whereby said bowl is supported by the ground support for tilting and bodily lifting and lowering; operating means to lift the bowl, from a forwardly inclined digging position, through a substantially level carrying position, to a rearwardly inclined very elevated dumping position; an apron to close the front end of the bowl; and means to operate the apron in the digging position.

6. A scraper according to claim 5, further characterized by the fact that the ground support is forked rearwardly, so as to permit a truck to back in under the bowl when the latter is raised.

7. A scraper according to claim 5, further characterized by the fact that the lower set of arms is upwardly cambered.

8. A scraper according to claim 5, further characterized by the fact that the lower set of arms is upwardly cambered; and that the ground support is forked rearwardly, so as to permit a truck to back in under the bowl when the latter is raised.

GEORGE W. MORK.
